UNITED STATES PATENT OFFICE.

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS.

MATERIAL-GATHERING MACHINE.

Application filed December 26, 1924. Serial No. 758,038.

This invention relates to improvements in material gathering machines for railways, and more particularly to machines adapted for use in gathering coal from the roadbed 5 of coal transporting rail systems, as for instance, in and about mines, where the coal drops from the cars, and often accumulates in such quantities as to interfere with the operation of the cars, and furthermore, is 10 wasted unless gathered systematically in such condition as to save it for fuel purposes.

The principal object of this invention is to produce a new and improved form of 15 gathering machine of the class described.

The invention may be best understood by reference to the accompanying drawings, in which:

Figure 1 is a view in side elevation of a 20 machine constructed in accordance with my invention;

Figure 2 is a plan view of the machine shown in Figure 1;

Figure 3 is an enlarged sectional view 25 taken on line 3—3 of Figure 1;

Figure 4 is a sectional view taken on line 4—4 of Figure 1;

Figure 5 is an enlarged sectional view 30 showing a detail of the conveyor mechanism, taken on line 5—5 of Figure 2.

Referring now to the details of the drawings, which illustrate one form in which my invention may be embodied, the loading machine proper comprises a main frame A, 35 mounted on a locomotive or similar supporting car B. The locomotive shown herein is of a well known mining type, having a frame 1, axles 2, 2, and supporting wheels 3, 3. A motor 4 is connected with one of 40 the axles and the locomotive is controlled from a motorman's cab 5 at one end thereof and having a controller 6 and a seat 7.

The loading machine frame extends longitudinally over the locomotive and is supported thereon by a swivel connection 10, which may be of any suitable construction, as shown herein comprising a king pin 11 extending through thrust bearing plates 12, 13 and 14, interposed between the loading 50 machine frame A and a support 15 on the locomotive B. A series of balls 16 are arranged in registering annular grooves in thrust plates 12 and 13 to afford rotation of the frame in a horizontal plane, and the 55 upper plates 13 and 14 engage each other

with curved bearing surfaces to permit limited rocking of the frame relative to the locomotive. Clearance is provided between the upper plate 14 and the king pin 10 to allow for this rocking movement. 60

The frame extends forwardly beyond the front end of the locomotive, and is supported on the track rails by a pair of wheels 20, 20. The frame is provided with devices at the front thereof for scraping and gathering 65 the loose material from the roadbed between and at the sides of the track, and with conveyor devices for raising this material and conveying it over and to the rear of the locomotive for discharge into a mine car C. 70

The gathering mechanism at the front end of the frame comprises a scoop 21, pivotally connected at 25, 25, to the frame just above the wheels 20, 20, and spreading somewhat wider than the frame so as to extend 75 on opposite sides of the rails, as clearly shown in Figure 2. The scoop is inclined forwardly as shown, and is notched at 22, 22 to receive the rails, so that the front edge 23 thereof is below the level of said rails. A 80 pair of runners 24, 24, are preferably arranged on each side of the notches 22, 22, these runners being turned upwardly at their front ends so as to assist in maintaining the scoop at the desired height from the 85 ground, and to raise the scoop over obstacles. The scoop is supported by means of a flexible cable 28 or the like, extending over sheaves 29 and 30 to a controlling lever 31 adjacent the motorman's station. 90

The rear end 33 of the scoop extends over a sill 34 of compartment 35 at the front end of the frame. This compartment is provided with two longitudinally extending conveyors 40 and 41 of the endless chain type, 95 which in the form shown comprise chains 40^a and 41^a respectively having cross bars 44 at suitable intervals for propelling the material along pans 40^b and 41^b of the respective conveyors. The conveyor 40 extends 100 the full width of the front end of the frame and its chain 40^a is trained at the front end over a pair of sprockets 42, 42 on shaft 45 beneath the rear end 33 of the scoop 21 and from thence, is inclined upwardly and rearwardly to a pair of sprockets 43, 43 on shaft 46. 105

The second conveyor chain 41^a is trained at its front end over sprockets 47, 47 on shaft 48 and extends upwardly over idler 110

sprockets 49 and 50 and thence rearwardly to the end of the frame, where it passes over sprockets 51, 51, on shaft 52. As will be observed in Figure 2, the rear conveyor 41 is narrower than the front conveyor 40, and is arranged at one side of the frame. A part of the material from the front conveyor is therefore discharged directly upon the rear conveyor while the portion of the material discharged laterally beyond the rear conveyor, falls upon an inclined apron 55, (see Figure 4) and is thus deflected toward and falls by gravity upon the rear conveyor. An upright partition 56 above the lower end of conveyor 41 keeps excess material from rolling forwardly off said conveyor. The conveyors are driven by a motor 57 through armature pinion 58 and gear 59, shaft 60, sprocket 61 and chain 62 extending to sprocket 63 on shaft 46 supporting the rear end of the front conveyor 40. The rear conveyor is also connected to the latter shaft by chain 64.

It will be observed in Figure 1 that the rear frame is cut away at one side and toward the rear thereof to afford room for the operator in the motorman's cab 5. This is accomplished by constructing the rear conveyor 41 relatively narrower and placing it to one side of the frame as shown. The loading frame is readily adapted to be detachably connected to any locomotive of the mining type and when not in use may be detached and the locomotive may be used for haulage in the usual manner.

Although I have shown and described one embodiment of my invention, it will be understood that the construction and arrangement of the various parts may be altered

without departing from the spirit and scope 40 thereof. Furthermore, I do not wish to be construed as limiting myself to the particular construction illustrated excepting as it may be specifically limited in the appended claims. 45

I claim as my invention:

1. In an apparatus of the class described, a frame having supporting means for pivotally mounting the same upon a locomotive, said frame having a scoop on the front end thereof, a pair of conveying devices for elevating the material from said scoop extending rearwardly over and to one side of said locomotive for discharging at the rear end thereof, one of said conveying devices having greater width than the other and extending laterally beyond the marginal limits of 50 said locomotive, and a motor carried by said frame for operating said devices. 55

2. In an apparatus of the class described, a frame having supporting means for pivotally mounting the same upon a locomotive, said frame having a scoop on the front end thereof, a pair of conveying devices for elevating the material from said scoop extending rearwardly over and to one side of said locomotive for discharging at the rear end thereof, one of said conveying devices having greater width than the other and extending laterally beyond the marginal limits of 60 said locomotive, a motor carried by said frame for operating said devices, and guiding means at the forward end of said frame 65 adapted to engage the rails. 70

Signed at Chicago, in the county of Cook 75 and State of Illinois, this 24th day of December, A. D. 1924.

THOMAS E. PRAY.
